UNITED STATES PATENT OFFICE.

HOWARD PERCIVAL MOORE AND FRANCIS HENRY GRIFFITHS, OF BIRMINGHAM,
ENGLAND.

MULTIPLE-SPINDLE DRILLING-MACHINE.

1,187,365.

Specification of Letters Patent. Patented June 13, 1916.

Application filed April 7, 1915. Serial No. 19,843.

To all whom it may concern:

Be it known that we, HOWARD PERCIVAL MOORE and FRANCIS HENRY GRIFFITHS, subjects of the King of Great Britain, residing 5 at Priory Works, Priory Road, Aston, Birmingham, England, and 8 Mayfield Road, Handsworth, Birmingham, England, respectively, have invented certain new and useful Improvements in Multiple-Spindle Drilling- 10 Machines, of which the following is a specification.

The invention provides an improved automatically acting vertical drilling machine of the multiple-spindle concentric kind, particularly suitable for drilling various kinds 15 of small articles.

In the machine according to the invention a combination of parts is provided whereby the drilling spindles may be conveniently set 20 either vertically or inclined upon supports which move around with a revoluble but otherwise stationary table which is positioned below the drills and carries a number of fixed and preferably interchangeable 25 work holders, means for automatically advancing the drilling spindles to the holders being applied above said spindles at the head or top of the machine in the form of stationary cam, inclined plane, or other suitable 30 devices contacting the upper ends of the spindles as the table, holders, and supports revolve about a common axis. Two, three, or more drilling spindles may be arranged upon the supports for each and every work 35 holder, and the latter and the table are fitted with vertically operating plunger-like grips which are spring moved to hold the work to the holders, and positively moved to release the work by devices arranged below the 40 surface of the table. The machine is built around a central column which centralizes the revolving table, and the drive for the table is arranged underneath the bed. The plungers holding the work in position on the 45 work holders are operated to release the work by a cam applied to the stationary bed of the machine underneath the revoluble table.

The invention is illustrated by the accompanying sheets of drawings.

Figure 1 shows a vertical section, with some of the parts in elevation, of the principal features of the machine. Fig. 2 is a horizontal section of Fig. 1 on the dotted 55 lines A. Fig. 3 is a horizontal section of

Fig. 1 on the dotted lines B. Fig. 4 shows an elevation of a part of the machine Fig. 1 illustrating the arrangement of a pair of spindles in respect of a work holder. Fig. 5 is a plan on a smaller scale of the cam which 60 automatically operates to release the work from the work holder. Fig. 6 is an underside plan on a smaller scale of the cam or inclined plane surface which automatically operates to feed the drills or other tools. Fig. 7 illustrates diagrammatically one manner of applying the driving belt to the pairs of spindles arranged according to the invention. 65

The stationary bed of the machine is at a 70 lifted by frame supports a^2 from the ground. Centrally supported at its lower end by the frame arm c and at its upper end by the frame arm c^2 is a truly vertical shaft or column d around which the whole of the machine is built. Revoluble around the shaft d is a work table e carrying a number of work holders e^2 which are interchangeable and arranged a distance apart in a circle near the boundary of the table where, at e^3 , said table 75 has bearings upon a ring of balls running in a half ball race of the bed and a half ball race of the table. The table is centralized by closely but loosely fitting the shaft d at e^4 , and is positively revolved upon the bed 80 by a gear such as the bevel wheel e^5 , rigidly attached to the underside of the table, a bevel pinion, e^6 , gearing with said bevel wheel and revolved by a short shaft e^7 , having bearings within the bed, and a plain 85 toothed gear e^8 revolving the shaft e^7 from a cone pulley e^9 ; said table being in this way 90 conveniently driven from its underside in a substantially concealed manner.

Rigidly secured within a ring recess f^2 of the bed a is a cam piece or lift f , which in conjunction with the bottom surface of the recess forms a cam ring. Carried by the table e to be operated upon by the cam piece 95 f are a number of vertical plungers g , one 100 for each work holder e^2 . Each plunger is downwardly traversed by a coiled spring g^2 . The lower end of the plunger is provided with a roller g^3 to contact the cam piece f , and the upper end of said plunger is provided with an adjustable grip g^4 operative 105 from the spring g^2 to hold the work down in a matrix h of the work holder e^2 ; the release of the grip being by the lift of the plunger from the cam piece f . 110

In Figs. 1 and 3 a hat and coat hook *i* is shown held down in the matrix *h* of the work holder while the operation of drilling it takes place, and it is a feature of this holding down that same is performed in a resilient manner while the plunger is off the cam piece *f*, and that the release of the work is positively carried out. Any suitable form of grip *g* may be used on the plunger *g*, but when adjusted it is a fixed part of the plunger which is always carried around with the table *e*.

For each work holder *e* a pair of drilling spindles *m* and *n* are provided. The bearings *m*² *n*² for these spindles are adjustably carried upon outwardly extending supports *o* and *r* formed integral with a sleeve *s* loosely fitting over the shaft *d* and at its lower end *s*² rigidly bolted to the work table *e*, said supports being common to all the pairs of spindles and always revolving with the table *e*. The construction of the drilling spindles and their bearings and the manner of application the one to the other forms no real part of the invention, but it is necessary for each spindle to be independently traversed in a direction away from the work by a spring *q*, and always toward the work in a positive manner, and that the axis of each spindle may be set either vertically or inclined upon the supports *o* and *r*. If the spindles are driven by a single belt, the belt pulley *t* of each spindle is also made to independently slide upon its spindle so as to compensate for the inclined position of the two spindles in respect of each other, the drawings showing an arrangement wherein a single belt drives all the spindles, but leaves a number of them stationary while the work is being changed in respect to the work holders.

Supported by a fixture near the upper end of the shaft *d* is the cam head *u* adapted to operate against the upper ends of all the drilling spindles for the purpose of feeding or moving the drills downwardly gradually into operative position. The face *u*² of the cam head is of ring form, and may form the active surface of a cam plate *u*³ which is an interchangeable feature in respect of the head, so that the drills may be moved or fed to operative position at various rates of speed and various operations be obtained by the requisitely shaped cam.

It will be clear that the cam head is a fixture, and that the spindles revolve with the table and always bear at their upper ends against the underside of said cam head by the operation of the spring *q*, an anti-friction ball, *w*, being applied between the end of each spindle and the cam face *u*².

The drills of the drilling spindles are indicated at *x*, but it is quite clear that same may be boring bits or any cutting tool which may become operative in a drilling spindle.

In the arrangement shown in the drawings there are six pairs of drilling spindles, and with a belt drive it is very easy to arrange by extending the belt around the pulleys *t* of the spindles, (as particularly shown in Fig. 7) so that either four or five pairs of spindles shall be rotated by the belt, while one or two pairs will be free of rotation and permit the work to be changed from their respective work holders, the right hand side of Fig. 1 showing a drill spindle and a work holder operative, and the left hand side a drill spindle stationary and the work holder inoperative.

With the machine aforesaid there is no waiting for the work to be drilled, as the operator of the machine is uninterruptedly feeding work, and the drilling of many articles is uninterruptedly taking place, one or two holes at a time, each time the work table makes a revolution, and, further, the feed of the drills is gradual and not under the control of the person feeding the work, so that the drills last longer without grinding.

Having now particularly described our invention what we claim and desire to secure by Letters Patent is:—

1. An automatic drilling machine of the character described comprising a revoluble table, a number of fixed and interchangeable work holders carried by the table, a plurality of drilling spindles disposed above said table and said holders, supporting means for said spindles and revoluble with said table, said spindles being arranged in the supporting means to be set either vertically or inclined, and cam means arranged above the drilling spindles to automatically operate against the upper ends of said spindles, substantially as described. 95

2. An automatic drilling machine comprising a revoluble table, a number of fixed and interchangeable work holders carried by said table, a plurality of drilling spindles disposed above said table and said holders, a pair of said spindles being provided for each holder and applied to supports moving around with said table, said spindles being arranged in the supports to be set either vertically or inclined, and fixed cam members arranged above the drilling spindles to automatically operate against the upper ends of said spindles, substantially as described. 110

3. An automatic drilling machine comprising a revoluble table, a number of fixed and interchangeable work holders carried by the table, a plurality of vertically operating grips spring moved to hold the work in the work holders and positively moved to release the work by devices arranged below the surface of the table, a plurality of drilling spindles disposed above said table and said holders and applied to supports moving around with said table, and cam means arranged above the drilling spindles to auto- 125

matically operate against the upper ends of said spindles, substantially as described.

4. An automatic drilling machine comprising, a revoluble table, a number of fixed and interchangeable work holders carried by the table, a plurality of vertically operating grips spring moved to hold the work in the work holders and positively moved to release the work from said holders, a plurality of drilling spindles disposed above said table and said holders, supports for the spindles and permitting vertical and inclined ad-

justment of the latter, said supports movable with said table, and cam means arranged above the drilling spindles to automatically 15 operate against the ends of the latter.

In testimony whereof we have hereunto set our hands in presence of two subscribing witnesses.

HOWARD PERCIVAL MOORE.
FRANCIS HENRY GRIFFITHS.
